PLANE

Robert W. Huxtable, Greenfield, Mass., assignor
to Millers Falls Company, Greenfield, Mass., a
corporation of Massachusetts

Application April 21, 1949, Serial No. 2,168

Term of patent 14 years

(Cl. D93—4)

To all whom it may concern:

Be it known that I, Robert W. Huxtable, a citizen of the United States, residing at Greenfield, in the county of Franklin and State of Massachusetts, have invented a new, original, and ornamental Design for a Plane, of which the following is a specification, reference being had to the accompanying drawing, forming a part thereof.

Figure 1 is a side elevational view of a plane showing my new design;

Figure 2 is a top plan view thereof; and

Figure 3 is an end elevational view looking from the left end of the tool as shown in Figs. 1 and 2.

I claim:

The ornamental design for a plane, as shown.
ROBERT W. HUXTABLE.
